PNEUMATIC WEAVING METHOD

Rudolf Wille, 52 Meraner Strasse, Berlin-Schoneberg, Germany, and Johannes Klein, 2 Harlingeroder Weg, Berlin-Charlottenburg, Germany

Filed Sept. 3, 1957, Ser. No. 681,772

15 Claims. (Cl. 139—127)

The method of air blast picking of the weft threads is, in general, already known in the weaving technique. As compared with the normal shuttle loom the pneumatic weaving process has the advantage of a remarkable increase of shot frequency, whereas at the same time the noise level is lowered to a great extent. Moreover, the blowing method even allows weaving of thin weft threads, e.g. monofil, or of thicker threads of poor strength or of small twist which could not be woven with a shuttle.

Pneumatic picking devices, known up till now, make use of the frictional forces as performed by an air jet on a thread carried along in the core of the said jet. The disadvantage of this method, however, is that the tangential forces active on the thread are only weak as the thread only offers a small surface area and as the coefficient of drag of the thread boundary layer is of no great value. For this reason, auxiliary means for increasing the friction have been used as for instance the addition to the air blast of atomized water or powder.

The main object of our invention is an improvement of the pneumatic picking process and a more effective use of the air blast energy.

A further object of our invention is the improvement of the attack of the air-flow forces on the weft thread.

Another object of our invention is to offer temporarily increased resistance of flow at the free end of the weft thread.

More in detail our invention consists in a method to arrange the forward end of the weft thread normally to the direction of the air blast. This can be put into practice by placing the said end of the weft thread in the form of a loop across the orifice of the blowing nozzle.

A preferred embodiment of our invention provides that the free end of the loop of the weft thread is fastened at the time of the beginning air blast and is then released so that it may uncoil in the direction of the shot.

Still another object of our invention is a mechanical device adapted to realize the aforementioned method. This device offers the special feature that the blowing nozzle is in coordination with a deflecting mechanism which draws the forward end of the weft thread across the orifice of the blowing nozzle.

These and other characteristics of our invention will be explained more in detail in connection with the drawings.

The drawings are representing our invention schematically and by way of example.

Figures 1 and 2 represent the positions of the weft thread in front of the blowing nozzle at different time intervals.

Figure 3 demonstrates the bringing up of the weft thread to the blowing nozzle which nozzle is drawn as a sectional view.

Figure 4 is a cross section on line A—B in Figure 3 of the blowing nozzle and its control element.

2

Figure 5 shows a modification of the thread guide as a horizontal section on line C—D of Figure 3.

Figure 6 gives a diagrammatic side elevation of the control mechanism for the clamping element for the weft thread.

Figure 7 is a plan view of Figure 6.

Figures 8 and 9 represent diagrammatically two phases of the fastening of the weft thread.

In Figs. 1 and 2, a metal plate 10 provides a nozzle 11 from which a jet of compressed air is discharged in the direction indicated by an arrow. The weft thread 12, which is passed through the nozzle 11 in the direction of the said arrow, is arranged in the form of a loop 14 running across the direction of the air jet in front of the nozzle orifice 13, so that the forces of the air blast are acting perpendicularly to the axis of the thread. When the weft thread starts to be propelled its forward end 15 is fastened or secured respectively by a clamping element 16 as indicated schematically in Figs. 1 and 2. The loop 14 is thus gradually widened up and stretched by the air jet as indicated by the dotted lines 14a and 14b in Fig. 1. After a certain growth of the loop 14 20 the clamping element 16 releases the free end 15 of the weft thread 12 which now can uncoil in the direction 25 of the shot, as indicated by the phases 15a, 15b, 15c in Fig. 2.

Due to the fact that, in accordance with our invention, the forward end of the weft thread is crossing the direction of the air blast and thus, provides a maximum of 30 resistance to said blast, the looped thread is propelled with great energy. During the process of uncoiling, the phases of which are given in Fig. 2, the moving mass of the deflected thread end is decreasing so that the free end of the weft thread moves with increasing acceleration 35 through the shed of warp threads, just as in the case of a whip crack.

Fig. 3 shows the weft thread 12 as delivered from a cross round bobbin 17. A conveyer belt 18, running over two drums 19 and 20 brings the weft thread to the 40 nozzle 11, an eye 21 serves for guiding the thread. The drum 20 is driven by the main drive of the loom whereas drum 19 turns freely. A spring supported roller 22, supported on a shaft 23, is guiding the weft thread 12 on drum 19. The frictional forces, growing up with 45 the angle of grip, are thus drawing off the thread from the bobbin 17 in a reliable manner.

The nozzle aggregate which blows the weft thread through the shed consists of a housing 24. A pipe 26 delivers compressed air to an annular chamber 25 of said 50 housing, and a rotary valve body 27 having two channels 28 and 29 and rotating in the housing controls the periodic flow of compressed air from the annular chamber 25 to the nozzle 11 provided in the housing 24. The rotary valve 27 revolving continuously intermittent air 55 blasts are impinging upon the weft thread which is drawn across the nozzle orifice as shown in Figs. 1 and 2.

The forces acting on the rotary valve 27 are supported by ball bearings 30 and 31. The rear end of the rotary valve is fitted with a gear wheel 32, the drive of which 60 is subject to further description.

From the cross section as shown in Fig. 4 it appears how the air pipe 26 and the annular chamber 25 communicate with the nozzle 11 during the relevant positions of the channels 28 and 29 of valve 27.

Whereas in Fig. 3 the weft thread 12 passes through an axial bore 33 of valve body 27 to the nozzle 11, Fig. 5 presents a solution wherein the housing 24 is provided with a lateral bore 34 more or less inclined to the axis of the nozzle 11, the weft thread 12 being carried through 70 said bore 34 to the front of the nozzle 11.

Figs. 6 and 7 show a side elevation and a top view of the housing 24 as described before. The above cited

gear wheel 32 of the rotary slide valve engages a pinion 35 which again communicates through a bevel gear drive 36 with a shaft 37. The said shaft carries a cam plate 38 which cooperates with the roller 39 of a rack 40. The rack 40 which may be shifted back to its starting position by the spring 41 mates a toothed segment 42 controlling the clamping element 16 as shown schematically in Figs. 1 and 2.

Owing to the fact that the rotary valve 27 is positively connected by way of the parts 32, 36, 38 and 40 to the toothed segment 42, the clamping element 16 works in synchronous rhythm with the nozzle 11. Accordingly, if the rotary slide valve reaches its position shown in Fig. 4 and if the weft thread 12 is positioned in front of the nozzle 11 as appearing from Fig. 1 the weft thread, following the various phases shown in Fig. 2, will be blown into the open shed where the reed 43 beats up the weft. At the side of the tissue opposite to the nozzle 11 the weft thread is bound up immediately after the beat, a gauze weave may aid this process.

In the course of the process as described before the clamping element denoted by 16 in Fig. 1, operates as follows:

The toothed segment 42 is supported by a shaft 45. This shaft also carries a clamping cam 46 co-ordinated with a cutting edge 47. In the drawing the said cam is shaped as a double sided clamping element. Opposite to and in the trajectory of the clamping cam 46, a spring biased abutment or support 49 is pivoted to a bracket 48 of the nozzle housing 24. If now the cam disc 38, in the rhythm of the rotation of the valve 27, pushes forward the rack 40 against the spring 41, and if the clamping cam 46 by way of the toothed segment 42 is turned upwards (see Fig. 6), the weft thread 12, as shown in Fig. 8 will be drawn against the spring support 49 where it is finally clamped between the parts 46 and 49 in a position as shown in Fig. 9, whereby the loop 14 demonstrated in Fig. 1 is formed. In the course of the sweeping movement the blade 47 cuts off the rearward end of the weft thread blown into the shed. This cycle of operations will be repeated at each 180° turn of valve 27 and at each corresponding shift of the gear rack 40. In the position as being shown in Figs. 1 and 9 respectively, the weft thread is attacked by the air blast and will be driven through the shed in the way shown in Fig. 2 whereafter it is cut at its rear end.

In the case of the clamping element being formed as a double sided cam (Fig. 6), the loop formation occurs by turns to both sides across the nozzle 11. It is understood, however, that the arrangement can also be made in such a way that the clamping element forms the loop always in one and the same direction.

The pneumatic thread-picking apparatus, as being shown in the drawings, can be arranged at both sides of the loom.

Moreover, it is to be mentioned that the feeding of the weft thread from the bobbin to the nozzle as well as the control of the nozzle itself could be constructed otherwise than in the manner shown in the drawings, without departing from the spirit of the invention.

What we claim is:

1. A device for pneumatic picking of weft threads comprising a nozzle for the discharge of compressed air in the direction of the shot, controlling means for the periodic delivery of compressed air to the nozzle, means for bringing up the weft thread to the nozzle and a deflecting mechanism adapted to draw the free end of the weft thread across the air nozzle.

2. A device for pneumatic picking of weft threads comprising a nozzle for the discharge of compressed air in the direction of the shot, controlling means for the periodic delivery of compressed air to the nozzle, the nozzle having an axial bore for said discharge through which the weft thread passes toward the warp, and a deflecting mechanism adapted to draw the free end of

the weft thread extending from said bore across the path of the air discharge from the nozzle.

3. A device for pneumatic picking of weft threads comprising a nozzle for the discharge of compressed air in the direction of the shot, controlling means for the periodic delivery of compressed air to the nozzle, a guide channel for the weft thread said channel ending near the air nozzle, means for bringing up the weft thread to the nozzle and deflecting mechanism adapted to draw the free end of said weft thread across the air nozzle.

4. A device according to claim 1 wherein the said deflecting mechanism comprises a clamping element.

5. A device according to claim 1 wherein the said deflecting mechanism comprises a clamping element in combination with a cutting blade adapted to disconnect the weft thread.

6. A device according to claim 1 wherein the said deflecting mechanism comprises a clamping element co-operating with a biased abutment.

20 7. A device for pneumatic picking of weft threads comprising a nozzle for the discharge of compressed air in the direction of the shot, a rotary valve for the periodic delivery of compressed air to the nozzle, means for bringing up the weft thread to the nozzle and a deflecting mechanism adapted to draw the free end of the said weft thread across the air nozzle.

8. A device for pneumatic picking of weft threads comprising a nozzle for the discharge of compressed air in the direction of the shot, a rotary valve for the periodic delivery of compressed air to the nozzle, means for bringing up the weft thread to the nozzle and a clamping element adapted to draw the free end of the said weft thread across the air discharge orifice, said rotary valve and said clamping element being coupled for synchronous action.

35 9. A device for pneumatic picking of weft threads comprising a nozzle for the discharge of compressed air in the direction of the shot, controlling means for the periodic delivery of compressed air to the nozzle, a driving mechanism for the said controlling means, a mechanism for bringing up the weft thread to the nozzle, a deflecting mechanism adapted to draw the free end of the weft thread across the air jet, a gear unit including a cam for the control of the said deflecting mechanism, the said driving mechanism and the shaft of the said cam being interconnected.

10. A method of picking weft threads, which comprises blasting a fluid jet in the direction of the shot and transversely against a weft thread arranged outside the warp shed across the path of the jet and by the force of the jet shooting the thread into the warp shed along said path in the form of a loop lengthening in said direction and extending within the shed across and along opposite sides of the jet.

55 11. A method of picking weft threads, which comprises blasting a fluid jet in the direction of the shot and transversely against a weft thread arranged outside the warp shed across the path of the jet and by the force of the jet shooting the thread into the warp shed along said path in the form of a loop extending across and along opposite sides of the jet, and then by the force of the flying loop uncoiling the thread forming one side of the loop to whip that thread across the shed in the direction of the shot.

60 12. A method of picking weft threads, which comprises blasting a fluid jet transversely against a weft thread arranged across the path of the jet and by the force of the jet shooting the thread into the warp shed in the form of a loop extending across and along opposite sides of the jet, and then by the force of the flying loop uncoiling the thread forming one side of the loop to whip that thread in the direction of the shot, and thereafter severing outside the shed the thread that formed the other side of said loop.

70 13. A method of picking weft threads, which comprises arranging a free end portion of the weft thread

across a shot path, and while holding the thread end in place blasting a fluid jet in said path transversely against the thread to shoot the thread into the warp shed in the form of a lengthening loop extending across and along the jet.

14. A method of picking weft threads, which comprises arranging a free end portion of the weft thread across a shot path, and while holding the thread end in place blasting a fluid jet in said path transversely against the thread to shoot the thread into the warp shed in the form of a lengthening loop extending across and along the jet, and then releasing said thread end so that said loop will uncoil to whip said end in the direction of the shot.

15. A method of picking weft threads, which comprises arranging a free end portion of the weft thread across a shot path, and while holding the thread end in

place blasting a fluid jet in said path transversely against the thread to shoot the thread into the warp shed in the form of a lengthening loop extending across and along the jet, and then releasing said thread end so that said loop will uncoil to whip said end in the direction of the shot, and thereafter severing said thread outside the shed to obtain a new end for arrangement across said path.
